UNITED STATES PATENT OFFICE.

JOHN STEPHEN MURPHY, OF NEW YORK, N. Y.

FORM-CLAMP.

1,190,940.

Specification of Letters Patent. Patented July 11, 1916.

Application filed July 29, 1915. Serial No. 42,565.

To all whom it may concern:

Be it known that I, JOHN S. MURPHY, a citizen of the United States, and a resident of the city of New York, borough of Brooklyn, in the county of Kings and State of New York, have invented a new and Improved Form-Clamp, of which the following is a full, clear, and exact description.

The invention relates to molds or forms employed in concrete construction work, and its object is to provide a new and improved form clamp arranged to securely connect the sides of a mold with each other and to prevent the same from spreading when filling in the concrete.

Another object is to permit of readily opening the form clamp for the removal of the mold sides and the clamp.

In order to accomplish the desired result, use is made of a main clamp member provided at one end with a hook and at the other end with an opening for the insertion of a wedge adapted to abut against the stud or other support, the hook being adapted 25 to hook onto a connecting member extending across the mold from one side to the other.

A practical embodiment of the invention is represented in the accompanying drawings forming a part of this specification, 30 in which similar characters of reference indicate corresponding parts in all the views.

Figure 1 is a sectional side elevation of an ordinary mold for building concrete walls and provided with the improved clamp, the section being on the line 1—1 of Fig. 2; Fig. 2 is a sectional plan view of the same on the line 2—2 of Fig. 1; Fig. 3 is a sectional side elevation of the clamp as applied to a floor mold; Fig. 4 is a similar view of 40 a modified form of the same; Fig. 5 is a longitudinal sectional elevation of the same on the line 5—5 of Fig. 4; and Fig. 6 is a side elevation of the clamp as applied to an abutment mold.

The sides of the mold illustrated in Figs. 1 and 2 consist of boards A, longitudinal braces B and studs C, the studs being spaced apart a suitable distance according to the thickness of the concrete wall to be built. Each of the studs C is preferably formed of two spaced members C' connected with each other at intervals by connecting blocks C". The boards A are provided with registering 55 apertures A' for the passage of a connecting member D provided at each end with one or more eyes D', the ends projecting beyond

the outer faces of the boards A. One of the eyes D' at each end of the connecting member D is engaged by a hook E' of a mold clamp E, preferably formed of a flat piece 60 of iron having a body E² provided with an opening E³ for the passage of a wedge F adapted to abut against the outer edges of the members C' of a stud C on the corresponding side of the mold. The wedge F is 65 preferably attached to one end of a chain G secured at its other end to one of the stud members C'. The body portion E² of each clamp E is also provided with a lengthwise extending guide slot E⁴ through which 70 passes a pin H driven through the stud member C' of a stud C. By reference to Fig. 1 it will be noticed that the hook E' extends at an angle from the outer end of the shank E⁵ forming an integral part of 75 the body member E², the arrangement being such that the hook E' is within the plane of the body portion E². It will be noticed that when the two clamps E are in engagement with the eyes of the connecting member D 80 and the wedges F are driven home, then the mold sides are not liable to bulge outward when filling in the concrete material between the mold sides. After the concrete material has set and it is desired to remove 85 the mold, it is only necessary for the operator to disengage the wedges F from the clamps E and to unhook the latter from the eyes of the connecting member D to allow 90 of removing the studs C and the mold sides, 95 and also to allow of finally removing the connecting member D. It will be noticed that by the arrangement described each clamp E and its wedge F form a permanent part of the corresponding stud C and hence the clamp E can be readily engaged 100 with the connecting member D and the wedge driven in place as above explained. It is understood that each clamp E can readily swing and slide on the pin H to engage the hook E' with the corresponding eye D' of the connecting member D.

When it is desired to hold a floor mold A² in place on the under side of I-beams I, then the hooks E' of the clamps E are 105 hooked onto the bases of the I-beams I and the wedges F are driven through the openings E³ against the under side of beams C³ supporting the mold boards A².

In the construction illustrated in Figs. 110 4 and 5 use is made of a connecting member J in the form of an L and hooked onto the

base of the corresponding I-beam I. The connecting member J is provided at its lower end with an eye J' into which hooks the hook E' of the clamp E engaged by the wedge F abutting against a sectional beam C⁴ similar to the stud C, it being understood that this beam C⁴ supports the bars C⁵ carrying the mold boards A³.

When forming concrete abutments or similar structures, as shown in Fig. 6, use is made of a connecting member K in the form of a piece of wire provided at its ends with loops or eyes K' engaged by the hooks E' of the clamps E held on the studs C, the same as above described in reference to the construction of the mold shown in Figs. 1 and 2, so that further description of the same is not deemed necessary.

Having thus described my invention, I claim as new and desire to secure by Letters Patent:

1. In combination, a mold having sides, studs engaging the sides, a connecting member extending transversely through the said mold sides and having eyes at the ends, clamps extending between the studs and each having an apertured body portion and a shank extending from the body portion and terminating in a hook, the hooks of the clamps being adapted to engage the eyes at the ends of the said connecting member, and wedges driven through the apertures in the body portions and abutting against the outer edges of the said studs.
2. In combination with a mold having sides, studs engaging the sides, a connecting member extending transversely through the said mold sides and having eyes at the ends, clamps each having an apertured body portion and a shank extending from the body portion and terminating in a hook, the hooks of the clamps being adapted to

engage the eyes at the ends of the said connecting member, the said clamps having lengthwise extending slots, pins adapted to be driven through the said slots into the sides of the studs, and wedges driven through the apertures in the body portions and abutting against the outer edges of the said studs.

3. In combination, a mold having sides, studs engaging the sides and each formed of spaced stud members, a connecting member extending transversely through the said mold sides and having eyes at the ends, clamps slidably mounted between the studs each having a body portion and a shank provided with an angular hook engaging the corresponding eye of the connecting member, the body portion of each clamp having an opening and the clamps extending between the stud members, and wedges driven into the said body openings and abutting against the outer edges of the said studs.

4. The combination with a mold side having an opening therein and beams engaging the side, of a clamp having a rectangular apertured body and provided with a shank projecting from one end thereof in direction of the length of the body and terminating in a hook for engaging a member, means for slidably mounting the clamp on a beam, and a wedge passing through the opening of the clamp and engaging said beam.

In testimony whereof I have signed my name to this specification in the presence of two subscribing witnesses.

JOHN STEPHEN MURPHY.
